(57) **CLAIM**

We claim the ornamental design for a bowl bag with utensil, as shown and described.

DESCRIPTION

FIG. 1 is a front view of the first embodiment of the bowl bag with utensil and tear line showing our new design; FIG. 2 is a rear view thereof; FIG. 3 is a top perspective view thereof; FIG. 4 is a bottom perspective view thereof; FIG. 5 is a side view thereof; FIG. 6 is a top view thereof; FIG. 7 is a bottom view thereof; FIG. 8 is a front view of the second embodiment of the bowl bag with utensil; FIG. 9 is a rear view thereof; FIG. 10 is a top perspective view thereof; FIG. 11 is a bottom perspective view thereof; FIG. 12 is a side view thereof; FIG. 13 is a top view thereof; and, FIG. 14 is a bottom view thereof.

In FIGS. 1-4 the longer dashed line represent tear line and is part of the claim. All other broken line showing portions of the bowl bag with utensil is included for the purpose of illustrating environmental structure and forms no part of the claimed design.

1 Claim, 8 Drawing Sheets
